Brace Pict of Hoboken N.J. Des 2496

Assignor to

St. Hubert's Clothing Co. of N.Y.

Letters Patent No. 8496. Dated Oct. 23, 1866.

Design for ornamenting a child's comb.

The schedule referred to in the above Letters Patent and making part of the same,

is as follows, it may concern:

Be it known that I, George Pict of Hoboken in the County of Hudson and State of New Jersey have invented or produced a new and original Design for ornamenting children's comb; and I hereby declare the following to be a full, clear and exact description of the same, reference being had to the accompanying drawing.

The Design which I have made the subject of the present application consists of steel plates or ornaments of different configurations and patterns as herein described which are arranged around the upper part of the comb and secured thereto by means of pins.

In the drawings I have shown the different patterns into which the steel is shaped, and the comb in the figure is represented by having secured to its upper part star shaped pieces of steel arranged in alternate order in a line parallel with the top of the comb, with other variously shaped steel pieces, all of which are shown.

What I claim and desire to secure by Letters Patent is,

The Design for ornamenting children's comb as herein shown and described

For testimony whereof, I have signed my name to this specification before two subscribing witnesses.

Witnesses

George Pict,

C. A. Durgin

Edward E. Olson.
